UNITED STATES PATENT OFFICE.

EARL G. WATROUS, OF CHICAGO, ILLINOIS.

WATER-CLOSET SYSTEM FOR RAILWAY-CARS.

1,270,902.

Specification of Letters Patent.

Patented July 2, 1918.

Application filed May 6, 1915. Serial No. 26,206.

To all whom it may concern:

Be it known that I, EARL G. WATROUS, a citizen of the United States, residing at Chicago, in the county of Cook and State of Illinois, have invented a certain new and useful Water-Closet System for Railway-Cars, of which the following is a specification.

My invention relates to a water closet system for railway cars and the like and the object thereof is to provide a system in which the discharge of a water closet is temporarily stored or retained in a suitable tank or reservoir which is in communication with the water closet or closets of the car and capable of being discharged from the tank or reservoir at any time and at any desired place and also while the car is in motion, such discharge being accomplished preferably by means of compressed air which may be supplied from a special air reservoir receiving compressed air from the air brake system. By means of this system the many disadvantages and inconveniences experienced in the present system of water closet as employed on Pullman cars and other railroad cars, in which system there is practically immediate discharge, are avoided, such as for instance the necessary locking of the closet rooms when the car is at terminals or at stations.

In the drawings Figure 1 is a sectional elevation illustrating one embodiment of my invention, and showing a part of a car floor, the closet thereon and the storage tank or reservoir communicating therewith together with the air pressure connections; Fig. 2 a side elevation of a part of the tank and the water closet discharge connection and the air supply connection; Fig. 3 a sectional view, on a larger scale than in the other views, of the valve mechanism for controlling the compressed air to the tank or reservoir, and Fig. 4 an elevation partly in section of a modified form of construction.

In the drawing I have shown and will hereinafter describe my present and preferred form of system without intention of limiting myself thereto except as expressly required by any specific claim.

Any suitable water closet of the jet type such as the one illustrated in Fig. 1 and marked 1 may be employed, the same being supported upon the floor 2 of the car. The discharge of the closet communicates with

a discharge pipe 3 which in turn communicates with the interior of the discharge tank or reservoir 4. As herein shown the discharge pipe 3 is connected by means of the 60 elbow 5 with a T-fitting 6 resting on top of the tank 4 and into which is screwed or otherwise secured the vertical discharge pipe 7 which in the present instance extends diametrically into the interior of the tank. 65

As shown the pipe 7 terminates near the bottom of the tank adjacent a bottom drain opening closed by the screw plug 8, a cavity or small well 9 being formed between the plug and the lower end of the pipe 7. By 70 preference, for a purpose hereinafter explained when the mode of operation is described, the lower end of the pipe 7 is provided with rounded edges, in the present instance by means of a shell 10 of the shape 75 shown according to which the lower edges are inturned and screw-threaded to screw upon the lower end of such pipe, thereby forming the rounded edges 10^a.

The fitting 6 is provided with a discharge 80 opening 11 which communicates with the higher discharge or delivery pipe 12 which is led any distance and to any point desired for the final delivery of the discharge of water and soil from the tank. 85

Referring to the compressed air connections and the valve mechanism therefore, such mechanism comprises a valve casing 13 having three separate connections, to wit, first the connection 14 communicating with 90 a source of compressed air, second a connection 15 leading into the top of the tank and third a connection 16 which in the present instance is shown as communicating with the fitting 6 and of course with the delivery 95 pipe 12 although as will be understood such connection 16 may run directly to the atmosphere. The connection 14 communicates with a passage 17 in the casing which terminates in a port 18 which port is governed by a valve 19. This valve has a stem 20 extending upwardly through the top of the casing and through the car floor and provided at its upper end within the car with the hand wheel 21 or the like, although any other type of valve such as a slow closing valve may be employed. The valve stem 20 is screw-threaded intermediate its length at 22 so as to be screwed up or down within the casing as the hand wheel 110 is turned in one direction or the other thereby opening or closing the valve.

When the parts of the valve mechanism are in the position illustrated in Fig. 3 the valve is seated to close the port 18 so that no air pressure can flow through such mechanism and the top of the tank is open to atmosphere through the connection 15, interior of casing 13, connection 16, fitting 6 and delivery pipe 12.

The discharge from the water closet passes through the pipe 3, fitting 6 and into pipe 7 and from thence into the tank, the same level being maintained in the tank and pipe 7. When it is desired to blow out or discharge the tank of its accumulated contents the operator 10 turns the hand wheel 21 in a direction to raise the valve 19 from its seat at port 18 and simultaneously the beveled upper side of the valve is seated upon the seat 23 within the casing. As a result 15 the communication between the top of the tank and the atmosphere is closed and the compressed air is admitted to the top of the tank, thereby exerting pressure thereupon and forcing the contents of the tank upwardly through the pipe 7, through port 11 and delivery pipe 12. The compressed air may be supplied until all or a portion of the contents of the tank, as may be desired, are discharged whereupon the valve 19 is operated 20 to close port 18 and to be open at its seat 23 whereupon the supply of compressed air is shut off and the tank relieved of pressure and opened to atmosphere. The purpose of the rounded or rolled-over edges 10^a at the lower end of pipe 7 is to prevent the catching 25 of toilet paper or the like upon the edge of the pipe which would otherwise be the case during the discharge of the contents of the tank.

In Fig. 4 I have shown a modified form 30 of construction which is the same as shown in Fig. 1 with the exception that there are added thereto two valves for controlling respectively the outlets of the discharge pipes 3 and 12, these valves being in the present 35 instance operable in unison and also automatically as an incident to the operation of the valve. In accordance with this modification there is arranged within the fitting 6 and at the end of the discharge of the elbow 5 which is connected to the pipe 3 a pivoted flap valve 24 which is secured to an axis or pin 25 projecting through one side of the fitting and connected to a bell crank 26. One arm of this bell crank is connected by 45 means of a link 27 to a lever 28 pivoted at its outer end to a stationary bracket 29 which is supported upon the valve casing 13. The arm 28 works between two collars 50 on the stem of the valve 21', with the result 55 that as such valve is screwed downwardly and the air consequently admitted to the top of the reservoir valve 24 is automatically moved from its normal vertical position 60 shown in Fig. 4 to a horizontal position,

closing the outlet of the discharge pipe 3 so that there will be no possibility of any discharge of the contents of the reservoir back into the discharge pipe 3 or of any backing up of such contents therein.

70

By preference the valve 24 operated in connection and in unison with another valve 31 which is pivoted at the outer end of the final discharge pipe 12, such valve being connected with the bell crank 26 by means 75 of the link or rod 32, with the result that as the valve 24 is moved to closed position the valve 31 is simultaneously moved to open position.

Although I have herein shown only one 80 water closet connected with the storage tank it will be understood that all of the water closets of the same car may be connected therewith.

I claim:

85

1. A water closet system comprising a water closet and its discharge connection, a storage tank, a substantially horizontal pipe communicating with the closet discharge connection and having a substantially vertical connection extending downwardly into the tank, said vertical connection acting both as a supply and a discharge for the tank and having a discharge outlet on a lower level than said horizontal pipe and 90 above the lower end of such vertical connection.

95

2. A water closet system comprising a water closet and its discharge connection, a storage tank, a substantially horizontal pipe 100 communicating with the closet discharge connection and having a substantially vertical connection with the tank, said vertical connection having intermediate its length a discharge outlet on a lower level than said 105 horizontal pipe, and fluid pressure means for discharging the contents of the tank through said vertical connection and its discharge outlet.

110

3. A water closet system comprising a 110 water closet and its discharge connection, a storage tank, a substantially horizontal pipe communicating with the closet discharge connection and having a substantially vertical connection with the tank, said vertical 115 connection acting both as a supply and a discharge for the tank and having a discharge outlet on a lower level than said horizontal pipe and above the lower end of such vertical connection, and a valve normally inoperative but arranged to close the communication between said horizontal pipe and the tank through said vertical connection.

120

4. A water closet system comprising a 125 water closet and its discharge connection, a storage tank, a substantially horizontal pipe communicating with the closet discharge connection and having a substantially vertical connection extending downwardly into 130

the tank, said vertical connection acting both as a supply and a discharge for the tank and having a discharge outlet on a lower level than said horizontal pipe, and 5 above the lower end of such vertical connection, said vertical connection and discharge outlet being arranged above the top plane of the tank, and fluid pressure means for discharging the contents of the tank 10 through said discharge outlet.

5. A water closet system comprising a water closet and its discharge connection, a storage tank, a substantially horizontal pipe communicating with the closet discharge 15 connection and having a substantially vertical connection extending downwardly into the tank, said vertical connection having a discharge pipe above the lower end of such vertical connection, a means of communication between the top of the tank and said discharge pipe, and valve mechanism therein for controlling said connection and arranged to admit fluid under pressure to the top of the tank.

25 6. A water closet system comprising a water closet and its discharge connection, a storage tank, a pipe communicating with said discharge and with the tank and having a lateral discharge opening, and manually operated means for admitting air under pressure to the tank to discharge the contents thereof through said opening.

7. A water closet system comprising a water closet and its discharge connection, a 35 storage tank communicating with said discharge and having a discharge opening and means whereby air under pressure is admitted to the tank to discharge the contents thereof through said opening, said means 40 comprising a valve casing having connections with a source of air under pressure, with the tank, and with the atmosphere, and a valve therein normally closing the connections with said source of air under pressure but arranged to open the same and simultaneously close the connection with the atmosphere.

35 8. A water closet system comprising a water closet and its discharge connection, a 50 storage tank, a pipe communicating with said discharge and with the tank, and having a discharge opening above the top plane of the tank and below the line of said pipe, and valve mechanism for controlling the admission of fluid under pressure to the tank 55 for discharging the contents through said opening and for the release of such fluid therefrom.

9. A water closet system comprising a 60 water closet and its discharge connection, a storage tank, a pipe communicating with said discharge and having a discharge opening, the said pipe entering the tank and extending to near the bottom thereof, and combined means for admitting air under pres-

sure to the top of the tank to discharge the contents thereof through said opening and for releasing the air therefrom.

10. A water closet system comprising a water closet and its discharge connection, a 70 storage tank, a pipe communicating with said discharge and having a discharge opening, at the top of the tank, the said pipe entering the tank and extending to near the bottom thereof, and combined means for admitting air under pressure to the top of the tank to discharge the contents thereof through said opening and for releasing the air therefrom. 75

11. A water closet system comprising a 80 water closet and its discharge connection, a storage tank, a pipe entering the top of the tank and extending to near the bottom thereof, said pipe communicating with said closet discharge and with an outlet to the atmosphere, and means for forcing the contents from the tank through said pipe and through said outlet.

12. A water closet system comprising a water closet and its discharge connection, a 90 storage tank, a pipe entering the top of the tank and extending to near the bottom thereof, said pipe communicating with said closet discharge and with an outlet to the atmosphere, and means for admitting air under 95 pressure to the tank to discharge the contents thereof through said pipe and through said outlet.

13. A water closet system comprising a water closet and its discharge connection, a 100 storage tank, a pipe entering the top of the tank and extending to near the bottom thereof, said pipe communicating with said closet discharge and with an outlet to the atmosphere, and means for forcing the contents of 105 the tank through said pipe and through said outlet comprising a valve casing having connections with a source of air under pressure, with the tank and with the atmosphere, and a valve therein normally closing the 110 connections with said source of air under pressure but arranged to open the same and simultaneously close the connection with the atmosphere.

14. A water closet system comprising a 115 water closet and its discharge connection, a storage tank, a pipe entering the top of the tank and extending to near the bottom thereof, said pipe communicating with said closet discharge and with an outlet to the atmosphere, the lower end of the pipe being rounded, and means for forcing the contents from the tank through said pipe and through said outlet. 120

15. A water closet system comprising a 125 water closet and its discharge connection, a storage tank, a pipe entering the top of the tank and extending to near the bottom thereof, said pipe communicating with said closet discharge and with an outlet to the atmos- 130

- phere, a shell fitting on the lower end of said pipe and having rounded lower edges, and means for forcing the contents from the tank through said pipe and through said outlet. 5
16. A water closet system comprising a water closet and a single discharge connection therefor, a storage tank, a pipe communicating with said discharge connection 10 and extending into the tank to near the bottom thereof, said pipe having a discharge outlet at a point intermediate its lower end and the point of communication with the discharge connection, means for discharging the contents of the tank through said outlet, and a valve for closing said discharge connection when the tank is being discharged of its contents. 15
17. A water closet system comprising a water closet and a single discharge connection therefor, a storage tank, a pipe communicating with said discharge connection and extending into the tank to near the bottom thereof, said pipe having a discharge 20 outlet at a point intermediate its lower end and the point of communication with the discharge connection, means for supplying fluid under pressure to the tank for discharging the contents thereof through said pipe and through said discharge outlet, and a valve under control of said means and operated simultaneously therewith for closing the said discharge connection when the tank is being discharged of its contents. 25
18. A water closet system comprising a water closet and its discharge connection, a storage tank, a substantially horizontal pipe communicating with the closet discharge connection and having a substantially vertical connection with the tank, said vertical connection having a laterally positioned discharge pipe, a means of connection between the top of the tank and said discharge pipe, valve mechanism therein for controlling 30 said connection and arranged to control the admission and control of fluid under pressure to and from the tank, and a valve for normally closing the discharge out of said discharge pipe. 35
19. A water closet system comprising a water closet and its discharge connection, a storage tank, a pipe having a substantially horizontal portion and a substantially vertical portion entering the tank and extending 40 to near the bottom thereof, said horizontal portion communicating with such discharge connection and said vertical portion having intermediate its length and extraneous of the tank a discharge outlet, means for supplying 45 fluid under pressure to the space above the contents of the tank for discharging such
- 50
- 55
- 60
- ing such contents upwardly through said vertical portion of the pipe and thence through said discharge outlet, said vertical portion acting both as a supply and discharge for the tank, and a valve under control of said means for governing said discharge outlet. 65
20. A water closet system comprising a water closet and its discharge connection, a storage tank, a pipe having a substantially horizontal portion and a substantially vertical portion entering the tank and extending to near the bottom thereof, said horizontal portion communicating with said discharge 70 connection and said vertical portion having intermediate its length and extraneous of the tank a discharge outlet, means for supplying fluid under pressure to the space above the contents of the tank for discharging such 75
